Primary Examiner — Nathaniel D. Buckner*(74) Attorney, Agent, or Firm* — Faegre Drinker Biddle & Reath LLP(57) **CLAIM**

The ornamental design for a woodworking featherboard, as shown and described.

DESCRIPTION

FIG. 1 is a front perspective view of a woodworking featherboard showing my new design in a first embodiment; FIG. 2 is a left side elevational view thereof; FIG. 3 is a right side elevational view thereof; FIG. 4 is a rear elevational view thereof; FIG. 5 is a front elevational view thereof; FIG. 6 is a top plan view thereof; and, FIG. 7 is a bottom plan view thereof. The broken lines in the drawings depict portions of the woodworking featherboard that form no part of the claimed design.
